Attorney.

UNITED STATES PATENT OFFICE.

JAMES B. McCaughey, of Pawtucket, Rhode Island.

DAMPER-REGULATOR.

No. 890,294.

Specification of Letters Patent.

Patented June 9, 1908.

Application filed January 10, 1908. Serial No. 410,192.

To all whom it may concern:

Be it known that I, JAMES B. McCaughey, a citizen of the United States, residing at the city of Pawtucket, in the county of Providence, State of Rhode Island, have invented certain new and useful Improvements in Damper-Regulators, of which the following is a specification.

My invention relates to a device for automatically regulating the dampers of steam and hot water boilers, and is a device essentially adapted for use in connection with boilers for heating dwellings.

The invention consists in combination with a time-clock having the usual auxiliary or alarm winding mechanism and hour-setting dial, of an adjustable bracket adapted to be secured to the ceiling and arranged to support the clock, a depending lever from an extension of said bracket and arranged to be held in a temporal position by the winding-stem of the auxiliary mechanism of the clock, and a latch-arm adapted to be pivotally mounted on the usual weighted cross-bar having chain-connection with the ash-pan damper and smoke-pipe damper of a boiler.

The object of my invention is to provide a device adapted to be actuated by the auxiliary winding mechanism of a time-clock, to automatically act at a certain fixed time, to release the weighted cross-bar having connection with said dampers and permit the latter to operate in retaining the heat of the boiler within the apartments of a dwelling.

My invention consists of the novel construction, arrangement and combination of parts, as hereinafter described and specifically set forth in the claims.

In the accompanying sheet of drawings, Figure 1 represents a perspective view of my improved device, as in operative position to regulate the dampers of a boiler. Fig. 2 is a front elevation of my device, showing a time-clock mounted thereon. Fig. 3 is a side elevation of the device, showing its releasing members in their normal or set position, and also indicating said members in dotted position, as when the device acts to operate the dampers, and, Fig. 4 is a rear elevation of the device, showing the winding-stem of the auxiliary mechanism of the clock, as engaging to temporarily hold the releasing members in their normal position.

Like reference characters indicate like parts, throughout the several views.

Referring to the drawings, *a* designates a bracket which supports a time-clock, whose mechanism actuates my improved device, and said bracket comprises respectively a tube *b* whose upper end is made fast in a plate *c*, which is secured by screws *d*, *d* to the ceiling of a boiler room; a circular band *f* having an integral hub *f*¹ arranged centrally at its upper portion and said hub adjacent to an integral extension *f*², and a shaft *g* having one end secured in the hub *f*¹ of said band and its free portion entering the tube *b*, in the manner shown in Figs. 2 and 3. A set-screw *h* is employed at the lower end of the tube *b*, to impinge against the shaft *g* in holding the band *f* in a fixed position.

A circular clock *i*, of the ordinary "alarm type", is mounted within the band *f*, which embraces the circular case *i*¹ of said clock, and said band is divided at its lower portion so as to dispose downward flanges *f*³, *f*³ which are perforated to receive therethrough a bolt *j* for clamping said band firmly upon the case of the clock. This clock is provided with the usual secondary or alarm mechanism (not shown) and its time-setting dial *j*².

A depending trip-lever *k* has its upper end pivoted to the extension *f*² of the circular band *f* and the lower end of said lever is yoke-shaped, as at *k*¹, to engage the end of a latch-arm *l*. This lever *k* has an integral flange *k*² arranged about midway its length to permit the cross-pin *m*, of the clock auxiliary mechanism, to engage thereupon and to hold said lever *k* in an inclined position towards the rear face of the clock, in the manner shown in full lines in Figs. 3 and 4.

The lower end of the latch-arm *l* is pivotally mounted on a stud *n* which is secured in the side of an inverted U-shaped piece *n*¹, and said stud is screw-threaded to receive a nut *n*² to impinge against in holding said arm in a fixed vertical position upon the member *n*¹. The upper end of the latch-arm *l* is cut away, on its side nearest the clock, so as to leave a narrow beveled shoulder to rest against the bottom edge of the yoke *k*¹ of the lever *k*. The U-shaped piece or saddle *n*¹ is adapted to be mounted upon the common cross-bar *o* having chain connection with the boiler-dampers, and said saddle is provided with a set-screw *n*³ to impinge against in holding the former in proper position upon said bar.

The lever *k* and arm *l* form the releasing members of my device. The cross-bar *o* is

pivots on an upright p , which extends from the top of the boiler q , and the saddle-piece n^1 , of the releasing member l , is secured at one side of the pivot center of said bar and at a point towards the front of the boiler, while the usual fixed weight r is secured at the other side of the pivot center of said bar and at a point towards the rear of the boiler, as shown in Fig. 1. A chain s connects from one end of the bar o to the ash-pan damper t , and a second chain s^1 connects from the other end of said bar to a lever u which is arranged to swing open the damper v of the smoke-pipe w , as in the ordinary arrangement of parts shown in Fig. 1.

Having now described the parts embodying my improvement, the operation of the device is as follows: Assuming the time-movement of the clock to be in operation and registering the time of hour as after ten at night, and it is desired to have the device regulate the boiler-dampers at—say five o'clock the following morning, the operator first winds up the auxiliary or alarm mechanism of the clock, by means of its winding-stem m^1 , after which the lever k is swung inwardly to its normal angular position to permit its flange k^2 to catch and rest upon the cross-rod m of said winding-stem, in the manner shown in Figs. 3 and 4, next, the stem x is turned in order to cause the hand x^1 to point toward the hour of 5 on the hour-setting dial i^2 , and finally the latch-arm l is swung over to engage the yoke-end k^1 of the lever k , thereby forcing down the bar o and causing the damper t of the ash-pan to close and at the same time cause the damper of the smoke-pipe w to open, as indicated by dotted position v in Fig. 1. As soon as the clock registers the hour of 5 its time-movement will actuate the auxiliary winding mechanism of the clock and thereby cause rotation of the winding-stem m^1 , thus releasing its cross-rod m from engagement with trip-lever k and as the cross-rod m revolves, its end portions strike against the upper part of the flange k^2 , which extends parallel with the lever k , and forces said lever from its normal angular position to a point closer to the clock, thus the yoke k^1 of the lever k is made free of contact with the beveled shoulder of the latch-arm l and the weight r carries said arm to the dotted position shown in Fig. 3, when the ash-pan damper will then have lifted to its opened position, as at t^1 in Fig. 1, and at the same time the damper of the smoke-pipe w will have closed by gravity, to the dotted position indicated at v^1 in said figure. Thus the heat of the boiler is retained to generate steam or hot water in the service pipes of the dwelling.

By having the bracket a designed in substantially two parts, one stationary part, as b , and the movable part, as g , telescoping the former, accommodates the device to be

readily adjusted to suit the height of distance between the cross-bar o of the boiler and the ceiling of its room.

By the simple arrangement of releasing members k and l , these parts permit of being readily adjusted to be operated upon by the rotative action of the winding-stem m^1 .

By my construction and arrangement of parts, I provide an automatic device that contains in itself all that is necessary to assure a proper working of the dampers of steam and hot water boilers, and at the same time a device that is simple, durable and inexpensive to manufacture.

What I claim and desire to secure by Letters-Patent, is—

1. In a damper-regulator for a boiler, the combination with a time-clock having an auxiliary mechanism, a stem for winding said mechanism, and an hour-setting dial, respectively, of a bracket adapted to be secured to a ceiling and having a support for said clock, said bracket having means to permit adjusting said clock in a fixed position, and also having an integral extension from its clock support; a depending trip-lever pivoted on the extension of said bracket and arranged to be held in an inclined temporal position by the stem of the winding-mechanism, and said lever having an integral yoke formed at its lower end; a cross-bar having connection with the dampers of a boiler; a saddle-piece adapted to be secured on said bar; and a latch-arm having one end pivoted on said saddle-piece and its free end to engage in the yoke of said lever.

2. In combination with a pivotally mounted cross-bar having chain connections with the ash-pan damper and smoke-pipe damper of a boiler, the herein described device, comprising a bracket constructed in substantially two members, one member in tubular form and adapted to be secured to a ceiling and the other member movably mounted in the stationary member, and second member having a divided band and also a lateral extension; means to secure both members of said bracket together; a time-clock secured by the band of said bracket and having an auxiliary mechanism, a stem for winding said mechanism, and an hour-setting dial, respectively; a swinging lever depending from the extension of said bracket and having its free portion inclined toward the clock and adapted to be held temporarily by the stem of the winding-mechanism; a saddle secured on the boiler-cross-bar; and a latch-arm pivoted on said saddle and having its free end to engage the free end of said lever.

3. In combination with a pivoted cross-bar having chain connections with the ash-pan damper and smoke-pipe damper of a boiler, of a device for regulating said dampers, comprising an adjustable bracket supported from the ceiling and having a lateral

extension; a time-clock mounted in the adjustable portion of said bracket, and said clock having an auxiliary mechanism actuated by the time-mechanism; a stem for winding the auxiliary mechanism and said stem provided with a cross-rod made fast in its outer end, and also an hour-setting dial, respectively; a trip-lever pivoted on and depending from the extension of said bracket, 10 said lever having an integral flange to rest upon the rod of said stem, and said lever having a yoke formed at its lower end there-

of; a saddle-piece secured on the cross-bar of the boiler; and a latch-arm pivoted on said saddle-piece and its free end to engage 15 in the yoke of said lever, all arranged substantially as shown and for the purpose specified.

In testimony whereof I affix my signature in presence of two witnesses.

JAMES B. McCaughey.
